(57) **CLAIM**

The ornamental design for a vehicle rear taillamp, as shown and described.

DESCRIPTION

FIG. 1 is a front and left side perspective view of a first embodiment for a vehicle rear taillamp;

FIG. 2 is a front, top, and left side perspective view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a rear and right side perspective view thereof;

FIG. 9 is a rear, top, and right side view thereof; and,

FIG. 10 is a rear view thereof.

The claim includes a second embodiment comprised of a mirror image of the vehicle rear taillamp as shown in FIGS. 1-10.

The broken lines and deemphasized areas within are shown for the purpose of illustrating portions of the article that form no part of the claim.

1 Claim, 10 Drawing Sheets
